UNITED STATES PATENT OFFICE.

WILLIAM G. FLANDERS, OF TROY, NEW YORK.

WASHING-MACHINE.

SPECIFICATION forming part of Letters Patent No. 259,636, dated June 13, 1882.

Application filed December 21, 1881. (No model.)

To all whom it may concern:

Be it known that I, WILLIAM GATES FLANDERS, of Troy, in the county of Rensselaer and the State of New York, have invented certain new and useful Improvements in Washing-Machines, of which the following is a specification.

The object of my invention is to make a cheap and simple utensil for washing clothes and articles requiring similar treatment, which shall perform the entire operation almost automatically; and the novelty consists in the peculiarity of the construction and combination of the several parts of the device, all as will now be more fully explained, and pointed out in the claim.

In the accompanying drawings, Figure 1 is a vertical central section of present device. Fig. 2 is a top plan view on line xx , Fig. 1, 20 plate D being removed. Fig. 3 is a plan view of the plate D, and Figs. 4 and 5 the detail of the valves.

The main vessel A is of any general form that may be desired. In practice the form 25 shown in the drawings is perhaps best adapted to the purpose. It is round, and provided near the bottom with an inwardly-projecting bead, e, which holds the perforated screen D in place by contact with its beveled hoop i. The boiler is also provided with a cover, F, 30 fitting snugly into the top by means of an ordinary hoop. A pipe, G, opening into the cover and terminating in the stove pipe or flue, allows the steam to escape up the chimney, 35 while the tightly-fitting cover prevents its escape into the room with the usual unpleasant results.

In the bottom of the vessel is fastened a comparatively shallow receptacle, B, smaller 40 in diameter than the vessel. This is also provided with a tightly-fitting cover, E. To this cover is fastened a vertical tube, C, extending upward to a point as near the top of the vessel as may be found necessary. This tube is 45 perforated with a number of small holes for the escape of steam and water. The form of this tube is not very material, though the conical shape shown is probably the most suitable. It will also follow that two or more may 50 be used, if desired.

Near the bottom of the inner receptacle, B, are holes a for the admission of water. Over these holes are hung, on suitable hinges, the inwardly-operating valves b b' b''. These are provided with weights o o, as shown, or may 55 have springs to close them automatically when the pressure of steam inside the receptacle is sufficient to counteract the weight of the surrounding water. A bridge, c, placed over the valves, prevents their opening beyond a certain 60 distance and protects them from accidents.

D is a screen-diaphragm with a central hole, M, through which the tube C passes, and outer holes, d d, for the free passage of water to and around the valves. It is held in place by contact of its beveled hoop i with the bead e in the vessel. Its purpose is to prevent the clothes or other articles from getting in the way of and clogging the valves. As will be seen, it is placed about in line with the top of the 70 cover of the inner receptacle.

The whole may be made of tin or other light material, and with slight modifications the working parts may be applied singly or doubly to an ordinary wash-boiler.

The process of washing and the action of the invention are briefly described as follows: The washer is placed on the stove, supplied with the requisite amount of water. The articles to be washed are put into the vessel around the 80 tube, with the dirtiest nearest to it. Soap is added to the water, the cover is put on, and the washer is ready for operation. The inner receptacle is now full of water, and the valves have closed by their own weight or by the 85 pressure of the spring, as the case may be. The water is raised to the boiling-point, when the steam generated in the inner receptacle escapes through the only outlet—the holes in the tube. This creates a vacuum, which forces 90 the water in this receptacle through the tube also with great energy. Practically there is no apparent difference in time between the escape of steam and that of the water. By a simultaneous action they rush through the perforations in the tube and strike the articles surrounding it with great force. At the same time the water outside the receptacle rises, which, in connection with the pressure of the escaping streams of steaming water, elevates the 95 100

articles several inches in the vessel. As soon as the force of the steam has become exhausted the water rushes into the receptacle again, the valves close, the clothes settle, and the blast 5 is again repeated. An intermittent action is thus secured, which keeps the articles in a state of agitation and permits the hot water to penetrate to every part of the surrounding mass and cleanse it thoroughly. This is continued until the dirt is entirely removed or until it may be found desirable to change the water. It will thus be seen that the only 10 manual labor required is in the handling of the washer, the water, and the articles washed, while the hard labor of scrubbing is wholly 15 dispensed with.

In Fig. 1 may be seen the action of the valves. b' represent valves open to take in water, and b'' shows the valve closed.

20 The action of the washer is very simple,

though positive. It requires no greater amount of heat to operate it than ordinarily employed in boiling clothes. Besides these advantages, it is inexpensive to manufacture, is so arranged that it is easily cleaned in every part, and is 25 not likely to get out of order.

Having thus described my invention, what I claim as new, and desire to secure by Letters Patent, is—

In a wash-boiler, as described, the combination of chamber B, having side openings, a , automatic valves b , and perforated pipe C, with a perforated screen or diaphragm, D, which fits close upon the top of B, all substantially as set forth.

WILLIAM GATES FLANDERS.
